US00D898555S

(12) United States Design Patent (10) Patent No.: US D898,555 S
LaPoint (45) Date of Patent: * Oct. 13, 2020

(54) BATHROOM HOLDER

(71) Applicant: Jean LaPoint, Lowell, MA (US)

CN 208510902 U 2/1919
DE 10206519 8/2003
WO 2003099059 12/2003

(72) Inventor: Jean LaPoint, Lowell, MA (US)

() Term: 15 Years

(21) Appl. No.: 29/687,425

(22) Filed: Apr. 12, 2019

(51) LOC (12) Cl. 08-05

(52) U.S. Cl.

USPC D8/355; D23/304

(58) Field of Classification Search

USPC D8/315, 316, 355, 349, 354, 311;
D23/303, 304

CPC A47K 3/40; E03C 1/04; C02F 1/42

See application file for complete search history.

(57) CLAIM

The ornamental design for the bathroom holder, as shown and described.

DESCRIPTION

FIG. 1 is a perspective front view of the bathroom holder, which embodies my design;

FIG. 2 is a left side view thereof;

FIG. 3 is a right side view thereof;

FIG. 4 is a front view thereof;

FIG. 5 is a rear view thereof;

FIG. 6 is a bottom view thereof;

FIG. 7 is a top view thereof;

FIG. 8 is a perspective view thereof;

FIG. 9 is another perspective view thereof; and,

FIG. 10 is another perspective view thereof.

Broken lines are used herein to show the environment in which the design is associated, and form no part of the claimed design.

1 Claim, 7 Drawing Sheets
